DESIGN FOR A PLASTIC SHEET OR SIMILAR ARTICLE

Eugene A. Dunn, Arlington, and Edward C. Gauss, Belleville, N. J., assignors to E. I. du Pont de Nemours & Company, Wilmington, Del., a corporation of Delaware

Application April 29, 1938, Serial No. 76,877

Term of patent 7 years

To all whom it may concern:

Be it known that we, Eugene A. Dunn and Edward C. Gauss, citizens of the United States and residents, respectively, of Arlington, in the county of Hudson and State of New Jersey, and of Belleville, in the county of Essex and State of New Jersey, have invented a certain new, original, and ornamental Design for a Plastic Sheet or Similar Article, of which the following is a specification, reference being had to the accompanying drawing, forming part thereof.

In the accompanying drawing:

The figure is a plan view of a plastic sheet or similar article embodying our new design.

The dominant feature of our design is the ornamentation appearing on the sheet and is independent of the thickness and configuration of the sheet.

We claim:

The ornamental design for a plastic sheet or similar article, substantially as shown and described.
